UNITED STATES PATENT OFFICE.

PIERRE RENARD AND ALBERT RENARD, OF NONANCOURT, FRANCE.

POWER LOOM FOR THE MANUFACTURE OF ORIENTAL, PERSIAN, WOUND, AND OTHER KNOT-STITCH CARPETS.

Application filed July 2, 1920. Serial No. 393,765.

(GRANTED UNDER THE PROVISIONS OF THE ACT OF MARCH 3, 1921, 41 STAT. L., 1313.)

To all whom it may concern:

Be it known that we, PIERRE RENARD and ALBERT RENARD, both citizens of France, and residents of Nonancourt, Eure, France, have 5 invented certain new and useful Improvements in Power Looms for the Manufacture of Oriental, Persian, Wound, and Other Knot-Stitch Carpets (for which we have filed applications for patents in France, Oc- 10 tober 31, 1913, No. 474,098; Holland, Jany. 31, 1914, No. 2390; England, March 8, 1917, No. 104690; and in Spain, Jany. 21, 1920, not granted), and of which the following is a specification.

15 As set forth in United States Patent No. 894,287 for power loom for the manufacture of tufted pile fabrics and in Patent No. 969,- 565, for loom for weaving oriental and other knot-stitch carpets, the formation of a knot 20 for oriental carpet on the loom depends upon a distributor and a knotting apparatus.

Under the action of the jacquard patterns, that is according to the design to be reproduced, the distributor brings the pile thread 25 from the various colored bobbins to the centre of distribution whence it is drawn out by a distributing gripper whose length corresponds to the height of the pile. The knotting apparatus seizes this portion of the 30 drawn thread which is cut off by shears at the distributing point, and knots the same upon the warp threads which are separated and stretched by a divider in the known manner.

35 In the first of the patents above mentioned, No. 894,287, the elements of the loom have a considerable size. A considerable spacing is found necessary in order to dispose the mechanism of grippers, shears and 40 divider between the distributors. This space occupied naturally limited the number of distributors and knotting apparatus on a loom, and the output was reduced accordingly.

45 The dispositions of Patent No. 969,565, already enabled the reduction of the space occupied by the elements and particularly by the shears disposed upon the looping device itself, but this was however not sufficient to provide for a large output.

The present invention is intended to eliminate all mechanism between the distributors so as to reduce their spacing to the minimum

represented by the length of the stroke of the distributing gripper.

Under these conditions, it will be readily observed that as the pile of the carpet becomes thicker, the pile thread to be distributed is longer, whence a less number of distributors can be mounted on the loom; conversely, as the pile becomes shorter, a greater number of apparatus can be disposed on the loom.

The accompanying drawings illustrate the invention.

Fig. 1 is a side elevation of a distributor with the corresponding gripper and divider;

Fig. 2 is a front view partly in section;

Figs. 3 and 4 shew in plan and in side elevation, respectively, a distributing gripper with its controlling mechanisms;

Fig. 5 shews one of the frames in which the supports of the grippers and their mechanisms and the shaft of the dividers are mounted;

Figs. 6, 7, 8 and 9 are detail views shewing how a divider is mounted and controlled.

Referring to Figs. 1 and 2, 1 is a distributor with converging blades 2; 3 is a distributing gripper, 4 is a divider, 5 the shaft thereof and 6 is the reed mounted on the batten 7.

Between two adjacent distributors 1; 1, there are no mechanical parts, the space being exclusively reserved for the passage of the threads to be distributed.

The gripper 3 is indicated on Fig. 2 only by its centre of oscillation 8 and by the lines 9, 10, indicating the position which it has on the one hand when it seizes the pile thread and on the other hand when it has fully extended the latter; these lines are inserted to show that the divider 4 has to oscillate in the vertical plane as indicated in mixed lines in Fig. 1, while the gripper 95 moves through the angle α (Fig. 2).

In its lowest position, the end 11 of the divider is nearly in contact with the batten and in its highest position it is at a level suitably above that of the centre 12 of distribution.

In Fig. 1, is also shown in dotted lines the warp of the weaving in its different stages of operation; it passes through the meshes 39 of a set of threads 38 controlled by the jacquard device and which raises the

same in the known manner. X—Y show the warp in the inoperative position; X'—Y' show it as raised by the divider above the centre of distribution; X—Y² show it in the 5 stretched position when the stitch is locked; this operation is set forth in the above named patents.

A number of frames 13 are arranged at suitable distances apart along the width of 10 the loom for supporting the distributors and the grippers and their mechanisms and also to serve as bearings for the shafts of the dividers. They have slots 14 and notches 15 and 16, for receiving fixed and movable bars, 15 and holes 17 through which extends the shaft of the dividers.

In notches 15 is fixed, extending along the width of the loom, a bar 18 which receives the pivots 19 of small flat levers 20, each 20 carrying two pins 21, 22 on which are threaded the eyes of the arms 23, 24 of the corresponding gripper. In the notches 16 can slide a bar 27 parallel to bar 18; to this bar 27 a cam imparts a longitudinal reciprocating movement and it carries fixed stops 25; in one direction of the movement each of these stops operates a lever 20 to open the gripper. In the movement in the contrary direction a spring 26 (Fig. 3) closes 30 the gripper.

In this construction, by adjusting suitably the stroke of the bar 27 and the tension of the spring 26, each gripper may have independent locking on each pile thread distributed. 35

The aforesaid oscillation of gripper represented by lines 9 and 10 (Fig. 2) is due to a bar 28 in which are embedded small stirrups 29 embracing each a gripper and 40 held in position by screws 30. This bar is parallel to bars 18 and 27 and like the latter has a longitudinal reciprocating movement due to a cam.

The stirrup 29 serves not only for moving 45 the gripper but also for adjusting its level so that the centre of the locking of the pile thread corresponds with the centre of distribution.

In Fig. 3 the ends of the two arms of the 50 stirrup embedded in the bar 28 are seen in plan. The screw which retains them and permits the aforesaid adjustments is not shewn.

Each divider has a cylindrical spindle 31 55 adapted to turn in a sleeve 32 which is driven into a transverse bore in the shaft 5 or is otherwise fixed in the shaft. This spindle carries at its end a pinion 33 accommodated in a cavity 34 milled in the shaft 60 5. This pinion is engaged with a rack 35, also fitted in the shaft and receiving a longitudinal reciprocating movement from a cam through a suitable device mounted coaxially with the shaft and allowing for the 65 oscillation of the latter on its axis.

The mechanism for rotating the divider is thus placed within the shaft and presents no exterior projection.

The sleeve 32 provides a long bearing for the divider, but it is not essential since the 70 spindle 31 may turn in the bore in the shaft. If sleeves 32 are used the holes 17 in frames 13 should be extended by slots 36 for passage of the sleeves in mounting the shaft.

By the construction described, two part 75 bearings on the frames, which are of little thickness, are avoided and the space occupied in the width of the loom is reduced. The dividers can only be mounted when the shaft itself is in place. 80

The arrangement within the shaft of the mechanisms controlling the rotation of the dividers constitutes the best construction, for then the gripper can be brought as close as possible to the shaft and there is no projection preventing the arrangement of the gripper tangentially to the shaft; the latter turns normally in the frames without impeding the reciprocation of the rack. This rack is retained merely by small caps placed 90 at suitable distances apart on the shaft, each between two grippers, that is to say, without impeding the function of the grippers. 85

However, it is not essential that the 95 pinions and the rack should be thus arranged; they might project above the shaft, but this modification would be to the detriment of the position of the gripper which would have to be inclined at a greater angle to the horizontal; also the bearings of the 100 shaft of the dividers in the frames shewn in Fig. 5 would have to be altered in order to allow the projecting rack to pass.

The notch 37 extending along the whole width of the gripper above the shaft of the 105 divider, permits the lowest possible level for the gripper and its opening and closing mechanism, without injury to its strength and efficient operation.

Having thus described the nature of our 110 said invention and the best means we know of carrying the same into practical effect, we claim:—

1. In a power loom of the character described, pile thread distributors arranged to 115 permit the free distribution of the threads between them, means including a gripper to distribute the pile thread below each distributor in substantially a horizontal direction, and a warp divider arranged below and 120 in the same vertical plane as the gripper and adapted to oscillate in an angular space determined above its axis by the two end positions of the gripper when it seizes the pile and when it has fully extended the latter. 125

2. In a power loom as claimed in claim 1, means to reciprocate the grippers comprising a horizontally reciprocating bar, and stirrups on the bar embracing the gripper.

3. In a power loom as claimed in claim 130

1, and in which each distributing gripper has two gripping arms on one end, means for opening and closing the arms comprising oscillating levers eccentrically pivoted to said arms, a horizontally reciprocating bar and means on the bar to oscillate said levers.

4. In a power loom as claimed in claim 3, and in which the means for oscillating the levers comprise pins on the horizontal bar 10 adapted to engage and move the levers in one direction, and springs connecting the bar and levers to move the latter in the op-

posite direction during the reciprocations of the bar.

5. In a power loom as claimed in claim 15 1, a bearing shaft for the warp dividers provided with recesses in which the dividers are rotatably mounted, pinions on the dividers, and a rack reciprocally mounted in the shaft in mesh with the pinions. 20

In witness whereof, we have hereunto signed our names.

PIERRE RENARD.
ALBERT RENARD.
